Primary Examiner — Susan Moon Lee(74) *Attorney, Agent, or Firm* — Hemisphere Law, PLLC(57) **CLAIM**

The ornamental design for a 3D scanner, as shown.

DESCRIPTION

FIG. 1 is a front elevational view of the 3D scanner;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an enlarged view of part of FIG. 1; and,

FIG. 8 is an enlarged view of part of FIG. 2.

The broken lines and unshaded portions contained within broken lines depict unclaimed features of the 3D scanner and form no part of the claimed design.
